GRILLE

Patrick Zampetti, 13 Van Buren Ave., and Robert Deuchler, 15 Hawthorne St., both of Cranford, N.J. 07016

Original design application Mar. 5, 1970, Ser. No. 21,774, now Patent No. 222,843, dated Jan. 11, 1972. Divided and this application Jan. 25, 1971, Ser. No. 109,725

Term of patent 14 years

Int. Cl. D25—02; D23—03
U.S. Cl. D54—2 A

FIG. 1 is a front elevational view of a grille showing our new design;

FIG. 2 is a top plan view thereof; and

FIG. 3 is a cross-sectional view thereof taken along the line 3—3 of FIG. 1.

The grille is broken away in FIGS. 1 and 3 to indicate indeterminate length. The brackets are shown in broken lines in FIGS. 2 and 3 for illustrative purposes only.

This is a division of our copending application Ser. No. D. 21,744, filed Mar. 5, 1970, for "Grille," now Pat. No. D. 222,843, Jan. 11, 1972.

We claim:

The ornamental design for a grille, as shown and described.
